UNITED STATES PATENT OFFICE.

WILLIAM SWEENEY, OF SEATTLE, WASHINGTON, ASSIGNOR, BY MESNE ASSIGNMENTS, OF ONE-HALF TO D. A. OLIPHANT, OF SEATTLE, WASHINGTON.

CIGARETTE-MAKING DEVICE.

1,413,809.

Specification of Letters Patent. Patented Apr. 25, 1922.

Application filed August 19, 1920. Serial No. 404,501.

To all whom it may concern:

Be it known that I, WILLIAM SWEENEY, a citizen of the United States, residing at Seattle, in the county of King and State 5 of Washington, have invented certain new and useful Improvements in Cigarette-Making Devices, of which the following is a specification.

This invention relates to a cigarette making device which may be conveniently carried in the pocket. The object of my improvement is to provide a strong, simple and efficient device of this character including a tobacco receptacle and cigarette making attachments which are arranged to occupy but little space.

Another object is to provide a cigarette making device by which a fine grade of cigarette may be quickly and easily rolled without spilling tobacco.

A further object is the provision of novel and efficient means for releasably retaining the cigarette forming tube and tube-filling plunger within the tobacco container and 25 serving to project said tube from the container when a cigarette is to be rolled.

With the above and other objects in view, the invention consists in the novel construction, adaptation and combination of parts 30 as will be more clearly hereinafter described and claimed.

In the accompanying drawings, Figure 1 is a view in longitudinal section of a cigarette making device constructed in accordance 35 with this invention shown in a closed position. Fig. 2 is a similar view showing the cigarette forming parts extended into operative positions. Fig. 3 is a sectional view through 3—3 of Fig. 1. Fig. 4 is a sectional view through 4—4 of Fig. 3; and Fig. 5 is a detached perspective view of a detail of the invention.

Like reference numerals designate like parts throughout the several views.

Referring to the drawings the numeral 6 designates a box-like receptacle having hingedly connected thereto a cover 7 and adapted to serve as a container for tobacco suitable for making cigarettes.

The box is provided in one end with a tubular bushing 8 that serves as a bearing through which a cigarette forming tube 9 may slide or telescope and in the other end of the box is provided a second bushing 10 55 which is in alignment with the bushing 8

and serving as a guide for a reciprocable tamping bar 11.

The tamping bar 11 is furthermore guided within a tubular member 12 having an integral bracket 13 by which it is rigidly secured as by screws 14 to the wall of the receptacle 6. The member 12 also serves as a guide for the cigarette forming tube 9 which telescopes thereover when in the closed position in which it is shown in Figs. 60 1 and 3. The member 12 has a longitudinally extending slot 15 in one side thereof for purposes hereinafter explained.

Two springs 16 and 17 preferably made from a single piece of wire and rigidly secured to the bracket 13 as by a clip 18 are provided for urging the cigarette forming tube 9 and the tamping bar 11 outwardly. The spring 17 has a movable end 19 that is arranged to project through an aperture 20 70 in the bar 11 and such spring 17 is provided with a hook 21 that is arranged to engage beneath an outwardly directed annular flange 22 on the top end of the cigarette forming tube 9. The hook 21 is preferably 75 made by doubling the wire that forms the end 19 of the spring 17 rearwardly, then looping the part that is doubled rearwardly over the main spring wire as at 23 and then forming the hook 21 on the extremity of 80 the wire.

The spring 16 is provided with a movable end 24 that rests upon and exerts a pressure on the top of the flange 22 and is guided within the slot 15 in the guide member 12. 85

The lower end of the tamping bar 11 is enlarged as at 25 to substantially the same diameter as the interior of the tube 9 to better facilitate the crowding of tobacco through such tube.

When the hook 21 is engaged beneath the flange 22 the tube 9 and bar 11 will be held in the positions shown in Figs. 1 and 3 in which position they will be out of the way so that the receptacle may be conveniently carried in the pocket. When a cigarette is to be rolled the finger is placed on the end of the bar 11 and such bar is pressed inwardly far enough to disengage the hook 21 from the flange 22 and thereby 100 permit the spring 16 to urge the tube 9 outwardly into a position as indicated by broken lines in Fig. 1. The bar 11 may then be released so that the spring 17 will move it outwardly into the position shown 105 110

in Fig. 2, and the tube 9 may be grasped by the fingers and pulled outwardly until the flange 22 strikes bushing 8 and prevents further outward movement thereof.

5 A cigarette paper 26 may then be wrapped around the tube 9 and may be twisted at the bottom as at 27 and held with the fingers of one hand as shown and the bar 11 may be reciprocated with the fingers of the other 10 hand to press tobacco outwardly through the tube 9 into the paper. As the paper fills with tobacco it will be moved outwardly on the tube and when full may be removed and have the other end twisted together to prevent 15 loss of the tobacco preparatory to lighting.

The tobacco will be packed sufficiently within the tube 9 to form a good cigarette that will draw easily but will not burn too freely.

20 After the cigarette is made the container may be inverted so that any tobacco that is left within the tube 9 will drop back into the container. The tube 9 and bar 11 may then both be pressed inwardly into the container 25 at the same time thereby causing the hook 21 to engage beneath the flange 22 and lock the said tube and bar in the position shown in Fig. 1.

When the tube 9 is telescoped within the 30 container the passageway therethrough will be closed by the guide member 15 and tamping bar 11 thereby preventing the passage of tobacco therethrough.

It will be understood that changes in the 35 form of construction, dimensions and arrangement of parts of this invention may be resorted to within the scope of the appended claims.

What I claim is,—

40 1. A cigarette making device comprising a tobacco receptacle, a rigid tubular guide member disposed within said receptacle, a cigarette forming tube slidable through one end of said receptacle and arranged to telescope 45 over said tubular guide member, a tamping bar slidable through the opposite end of said receptacle and through said tubular guide member and arranged to telescope within said cigarette forming tube and a 50 spring which is adapted to be used for yieldingly retaining the tamping bar in its inner or outer positions, selectively, said spring also serving to releasably retain said forming tube in its inner position.

55 2. A cigarette making device comprising a tobacco receptacle, a cigarette forming tube arranged to telescope within said receptacle from one side, a tamping bar arranged to telescope within said receptacle from an op-

posite side and to project within said cigarette forming tube, springs for urging said cigarette forming tube and said tamping bar outwardly, and releasable catch means for holding said cigarette forming tube and said tamping bar inwardly against the pressure 60 of said springs.

3. A cigarette making device comprising a tobacco receptacle, a tubular guide member rigidly supported within said receptacle, a cigarette forming tube slidable through one 70 end of said receptacle and arranged to telescope over said tubular guide member, an outwardly directed annular flange on the inner end of said cigarette forming tube, a tamping bar slidable through the opposite 75 end of said receptacle and through said tubular guide member, a spring secured to said tubular guide and projecting in opposite directions therefrom one end of said spring being arranged to exert an outward pressure 80 on said cigarette forming tube and the other end of said spring being arranged to exert an outward pressure on said tamping bar, and a catch hook connected with the last named end of said spring and arranged to 85 engage beneath the flange on the inner end of said cigarette forming tube.

4. A cigarette making device comprising a tobacco receptacle, a tubular guide member rigidly supported within said receptacle said 90 guide member having a slot extending lengthwise thereof, a cigarette forming tube telescopic through one end of said receptacle and arranged to fit over said guide member, an outwardly directed annular flange on the 95 inner end of said cigarette forming tube, a tamping bar arranged to telescope through the opposite end of said receptacle and to project through said tubular guide member and into said cigarette forming tube, a spring 100 wire secured to said tubular guide member and projecting outwardly therefrom in opposite directions and thence back toward said guide member to form two springs the end of one of said springs being guided within 105 the slot in said guide member and arranged to exert an outward pressure on said tube and the end of the other spring being arranged to urge said tamping bar outwardly, and a hook secured to the end of said tamping 110 bar spring and arranged to engage beneath the flange on said tube.

Signed at Seattle, Washington, this 12 day of August, 1920.

WILLIAM SWEENEY.
